UNITED STATES PATENT OFFICE.

MAURICE LACHMAN, OF NEW YORK, N. Y.

DESIGN FOR A FENCE.

47,111.

Specification for Design.

Patented Mar. 16, 1915.

Application filed December 17, 1914. Serial No. 877,822. Term of patent 7 years.

To all whom it may concern:

Be it known that I, MAURICE LACHMAN, a citizen of the United States, and a resident of the city of New York, borough of Manhattan, in the county of New York and State of New York, have invented a new, original, and ornamental Design for Fences, of which the following is a specification, reference being had to the accompanying drawings, forming part thereof, in which—showing my new design. Fig. 2 is a transverse section of the same taken on the line 2—2.

I claim:

The ornamental design for a fence, as shown.

MAURICE LACHMAN.
